DESIGN FOR A LIGHTING FIXTURE REFLECTOR

Morris B. Beck, Woodmere, N. Y.

Application June 19, 1935, Serial No. 57,336

Term of patent 3½ years

To all whom it may concern:

Be it known that I, Morris B. Beck, a citizen of the United States and a resident of Woodmere, Long Island, county of Nassau, and State of New York, have invented a new, original, and ornamental Design for a Lighting Fixture Reflector, of which the following is a specification, reference being had to the accompanying drawing, forming part thereof.

Figure 1 is a view in perspective of a lighting fixture reflector showing my new design, the re-

flector being shown as it would appear when in ordinary use;

Figure 2 is a side elevation thereof with a portion in section; and

Figure 3 is a sectional view on the line 3—3 of Figure 2.

I claim:

The ornamental design for a lighting fixture reflector as shown.

MORRIS B. BECK.
